UNITED STATES PATENT OFFICE

112,072

DESIGN FOR A BUILDING

Eugene Kaplan, Boston, Mass.

Application June 20, 1938, Serial No. 77,957

Term of patent 14 years

To all whom it may concern:

Be it known that I, Eugene Kaplan, a citizen of the United States, residing at Boston, in the county of Suffolk and State of Massachusetts, have invented a new, original, and ornamental Design for a Building, of which the following is a specification, reference being had to the accompanying drawing, forming part thereof.

I claim:—

The ornamental design for a building, as shown.

EUGENE KAPLAN.
